DEVICE FOR AND METHOD OF MAKING FIBROUS CONES AND THE LIKE

Application filed March 26, 1928. Serial No. 264,796.

The present invention relates to devices for and methods of making fibrous articles, such as cones for sound reproducers and other like and similar objects.

5 Among the objects of the invention is to provide a novel method for making a fibrous article, such as a cone or other like and similar objects, of varying thicknesses at different parts or points, as for example, in 10 the case of the cone, the thickness may vary progressively from apex to border or vice versa. This may be effected by use of a porous former, which may be progressively moved into and out of a fluid bath of suspended fibers, the part first entering the bath being longest in immersion, and hence receiving the greatest deposit of fibers, the part last entering the bath having the least immersion, and hence the smallest deposit 15 of fibers. In the case of reciprocating the movement of the former, the part first to enter the bath is the last to leave it on the return stroke, and similarly the part last to enter the bath is first to leave it on such 20 turn stroke. In this way different parts of the former are in immersion for different periods of time. Suction is effected during all of the time of movement whereby the fibers may be sucked upon the former on 25 such portions as are immersed, and hence such parts that are immersed the longer or longest in time relation will receive the greater or greatest deposits of fibers, and likewise such parts as are immersed the shorter or 30 shortest in time relation will receive the lesser or least deposits of fiber. The variations in thickness are, therefore, gauged by the rate of movement of the former into and out of the bath and the amount of suction or 35 partial vacuum in the former or former head. The movement may be regular or uniform to produce regular gradations in thickness variation, or the movement may be irregular. In the latter case, the variations or successions 40 of deposits of successive parts of the former may be such as to form ribs, corrugations, or the like, the deposits being thicker at the slow regions to effect hills and thinner at the fast regions to effect valleys.

45 It is also an object of the invention to pro-

vide a novel article by the method mentioned, also, to provide a novel device or means for carrying out the process mentioned and to produce the article mentioned. In a specific embodiment illustrative of the invention, the device comprises a container for the fluid bath of suspended fibers, fibrous material, or pulp, or the like, and means may be used for agitating the bath for maintaining the fibers in substantially homogeneous suspension. The 55 former is preferably of porous form and placed upon or in contact with a perforated part or portion of a head, which is preferably hollow so that a partial vacuum may be produced or effected therein to cause a suction of the fluid from the bath through the pores and perforations of the former and head, and thus effect a deposit of fibers on the former. Means is preferably connected to the head and adapted to move the same into 60 and out of the bath at given rate so that the parts of the head may be made to progressively or successively enter and leave the bath, as 65 above explained.

70 Other objects, capabilities, advantages, features and process steps are comprehended by the invention as will later appear and are inherently possessed thereby.

75 Referring to the drawings, Fig. 1 is a view partly in side elevation and partly in vertical section of a device constructed in accordance with the invention;

Fig. 2 is a top plan view of the same;

Fig. 3 is a fragmentary vertical sectional view of the head part and parts of the container and operating mechanism;

Fig. 4 is a vertical sectional view of a former and a blank thereon;

Fig. 5 is a similar view of a fibrous blank;

Fig. 6 is a fragmentary view of the device 80 altered to use a former in reverse position, for increasing the thickness gradually in an opposite direction from that in the former shown in the other figures.

95 Referring now more in detail to the drawings, the embodiment selected to illustrate the invention is shown as comprising a container or vat 1 in which is included a given amount of liquid and suspended fibers 2. This fluid bath with suspended fibers may be 100

maintained in agitation by the blowing of air through a perforated coil 3 located in the lower part of the container or bath, and connected to an air inlet pipe 4 controlled by a valve 5 as clearly shown in Fig. 1.

Associated with the container or vat 1 is a frame having uprights 6 and 7 connected to the vat by angle pieces 8 and 9 at the lower end thereof, and by guide pieces 10 and

11 connected to the upper end of the vat and acting as guide elements as will be later explained. To the upper parts of the members 6 and 7 are connected cross members or beams 12 and 13, the beam 13 being connected to the

uprights 6 and 7 by plates 14 and 15, as clearly shown in Figs. 1 and 2 of the drawings. To the beam 13 are secured angle brackets 16 and 17 and guide strips 18 and 19, the strips being spaced from the brackets

20 to provide guiding channels or tracks for the sliding of vertically reciprocated angle bars 20 and 21. These angle bars may also carry or have secured thereto, side strips 22 and 23

25 adapted to slide over the outer edges of the angle brackets 16 and 17, as clearly shown in Fig. 2. To each angle member 20 and 21 are attached toothed racks 24 and 25 in any suitable manner. With the racks are meshed gears 26 and 27 driven by shaft 28 rotatably

30 supported in bearings 29 and 30 carried by brackets 31 and 32 secured to the sides of the members 6 and 7 as clearly shown in Fig. 1. Collars 33 and 34 may be secured to the shaft adjacent to bearings to prevent axial

35 movement of the shaft.

To the upright member 6 and at a suitably elevated point, is secured a platform or shelf 35, upon which is mounted a motor 36 in driving connection with a gearing device 37 of 40 any suitable type. The motor is coupled to the gearing through a coupling 38, and the gearing is coupled to the shaft 28 by a coupling 39. The gearing 37 is such that it is capable of rotating the shaft in one direction 45 for a given time and then reversing the direction of rotation, so that the racks 24 and 25 and connected parts may be vertically reciprocated.

At the lower ends of the reciprocating members 20 and 21 are secured brackets 40 and 41, upon which is supported and may be secured a plate 42. This plate may be provided with a threaded opening for connection of a nipple 43, carrying an elbow 44 to 50 which may be connected a flexible duct or pipe 45. The pipe is connected to a pipe 46 extending through a side wall of the vat and leading to any suitable means for creating a suction or partial vacuum, the passage being controlled by a hand valve 47 as desired. Upon the plate 42 may be supported or otherwise engaged a perforated cone shaped plate or head member 48. The thickness of this plate and the size of the perforations are 55 exaggerated for the purpose of clarity,

Upon the head member 48 is placed a thin metal member 49 which may be perforated or porous and of cone shape, fitting with the outer surface of the member 48. This porous member 49 has very fine perforations, or 70 may be of the reticulated form. The fibrous material 50 is deposited upon this porous member in the form of a blank as will be later explained.

It will be noted that the reciprocable members 20 and 21 are slidable in grooves or slots formed in the brackets 10 and 11 on the top of the vat so as to guide the vertical movement of the members 20 and 21. 75

In the alternate form shown in Fig. 6, the plate 42a is secured to brackets 40a and 41a so as to hold the head beneath the plate instead of above the same as in Fig. 3. In other respects the head comprises the perforated head member 48, a porous spinner 49 85 upon which is deposited the fibrous material 50 upon the under side rather than upon the upper side, as in Fig. 3.

In the operation of the device, a given quantity of water and fibrous material is 90 maintained in the vat and the agitation of the same is effected so as to maintain the fibers in suspension and in more or less homogeneous condition. At the start, the reciprocating means is in upper position with 95 the porous head above and outside the vat. The suction device is operated so as to create a partial vacuum within the space between the head member 48 and the plate member or portion 42, so as to cause a suction through 100 the perforations and pores of the members 49 and 50. The motor is then started and as it drives through the gear mechanism, this being of the reduction gear type, the shaft 28 and gears 26 and 27 are rotated in the proper manner to lower the racks 24 and 25, and the porous head. This is done at a given rate so that as the lower part of the porous member enters the bath, the fibrous material will begin to be deposited upon that 105 part being immersed. This will progress until the head is completely immersed and reaches the position shown in full lines in Fig. 1 of the drawings. It is seen from the above that the lower part of the porous head has been immersed a longer time than the upper part of the head, and that a greater amount of fibers will be deposited upon the parts that have been immersed the longer 110 time. The movement of the head is then reversed, caused to rise and leave the bath. It will be noted that the upper part of the head will leave the bath earlier than the lower part will, and the parts remaining in 115 immersion will be having fibers deposited thereon, so that a greater amount of fibers will be deposited on those parts leaving the bath later than the parts leaving the bath earlier. In this way there is a gauged or 120

125

130

graduated thickness of deposited fibers from apex to border, or vice versa, of the cone.

In the form shown in Fig. 3 the thicker deposit is at the border of the cone, while the thinner deposit is at the center. In the form shown in Fig. 6, the thicker deposit is at the apex and the thinner deposit at the border.

It will be understood that the gearing member 37 may be so designed as to reciprocate the head at an irregular rate, so that the immersion may be for certain distances rather rapid, and for other distances or regions slow, so that the deposit of fiber may be made less or greater according to the rate of immersion and time of immersion of these regions.

While I have herein described and upon the drawings shown an illustrative embodiment of the invention and a process of producing the particular articles disclosed, it is to be understood that the invention is not limited thereto, but may comprehend other constructions, arrangements of parts, details, process steps and features without departing from the spirit thereof.

Having thus disclosed the invention,

I claim:

1. The process of making fibrous cones for sound reproducers, comprising immersing successive parts of a porous former in a fluid bath of suspended fibers whereby different points of the former will be immersed for different lengths of time, and causing depositing of fibers upon the former in thicknesses at different points proportional to the time of immersion of said points.

2. The process of making fibrous cones for sound reproducers, comprising progressively moving a porous former into and out of a fluid bath of suspended fibers, creating a suction within the former, causing a deposit of fibers upon the immersed parts of the former, the thickness of fibers deposited being proportional to the time of immersion of said parts.

3. A fibrous cone varying in thickness from apex to border.

4. A fibrous cone composed of a layer of deposited fibers from a fluid bath of suspended fibers, said layer of fibers being of a thickness over portions of the cone according to the time of immersion of said portion in said bath.

5. A fibrous cone composed of a layer of deposited fibers from a fluid bath of suspended fibers, said layer of fibers varying in thickness from apex to border in proportion to the time of immersion of said cone in said bath.

6. A fibrous cone composed of deposited fibers from a fluid bath of suspended fibers, different successive parts of said cone between the apex and the border of said cone having different thicknesses of deposited

fibers proportionate to the time of immersion of said parts in said bath.

7. The process of making fibrous objects comprising immersing a porous former in a bath containing fibers in suspension, causing said fibers to deposit upon said former while the former is immersed in said bath, and varying the thickness of said deposit by varying the period of immersion of predetermined parts of said former.

8. A device for making fibrous articles comprising a container for holding a bath carrying fibers in suspension, a hollow porous former, a support for said former, said support being movable, so that the former may be immersed in and removed from said bath, means for producing a difference of pressure outside of and within the former, so as to cause fibers to deposit thereon, and means for so controlling the speed of movement of said support that some portions of the former are immersed in the bath sufficiently longer than other parts thereof to provide a varied thickness of deposited fibers.

In witness whereof, I hereunto subscribe my name to this specification.

ALBERT NEWCOMBE.
